UNITED STATES PATENT OFFICE

2,067,543

LAUNDRY SHAKE-OUT TUMBLER

Edward D. Purkett, Joplin, Mo., assignor to Purkett Laundry Company, Joplin, Mo., a corporation of Missouri

Application July 26, 1935, Serial No. 33,355

8 Claims. (Cl. 259—81)

This invention relates to laundry shake-out tumblers, and is an improvement over the apparatus described and claimed in my prior Patent No. 2,002,796, granted May 28, 1935. 5 In laundry practice, such articles as towels, sheets, etc., are ordinarily twisted or wrung until nearly dry, after they have been laundered. The articles are then subjected to a rather severe shaking out to loosen them up preparatory to feeding them to the ironers. For example, a substantial amount of labor is involved in manually shaking out the articles and the ironing operation does not produce particularly satisfactory results.

15 In my prior patent referred to I provide a tumbling cylinder rotatable to lift and drop the articles without any attention on the part of the operator, and after the articles have been in the apparatus a predetermined length of time, the tumbler is rotated to a discharging position to drop the articles upon a table from which they may be readily picked up and fed to the ironers. The articles thus discharged to the table are in a loose condition particularly satisfactory for ironing, without the use of labor in performing the shaking-out operation.

An important object of the present invention is to provide a novel shake-out tumbler which eliminates the rack and pinion means of my prior 30 patent referred to which was employed for bodily moving the tumbler to facilitate the discharging operation, the present invention involving a tumbler which is preferably rotated about a fixed axis from its loading and operating position to its discharging position.

A further object is to provide an apparatus of the character referred to wherein the discharging operation may take place relatively higher than the loading operation, thus facilitating the loading of the apparatus and permitting the discharging 40 of the articles to an ordinary receiving table.

A further object is to provide a laundry shake-out tumbler of the character indicated wherein the position of the parts may be readily varied 45 to provide any desired difference in the loading and unloading heights.

A further object is to provide an apparatus which occupies one position when being loaded and operated and which is adapted to swing about 50 a fixed axis to an unloading position in which the opening in the tumbler faces downwardly to facilitate the discharging of the articles from the tumbler during the continued rotation thereof.

A further object is to provide a shake-out tumbler wherein the center of mass of the tumbler

and its associated parts is so arranged as to bias the tumbler away from its discharging position to its loading position whereby the tumbler will automatically move to the latter position upon the releasing of a suitable latch after the articles 5 have been discharged from the tumbler.

A further object is to provide such an apparatus which is biased away from both its loading and unloading positions to facilitate the movement of the tumbler from each of its two positions to the other position.

Other objects and advantages of the invention will become apparent during the course of the following description.

In the drawings I have shown one embodiment 15 of the invention. In this showing:

Figure 1 is a front elevation,

Figure 2 is a side elevation,

Figure 3 is a central vertical sectional view on line 3—3 of Figure 1,

Figure 4 is a sectional view taken substantially on line 4—4 of Figure 1,

Figure 5 is a vertical sectional view on line 5—5 of Figure 1,

Figure 6 is a horizontal sectional view on line 6—6 of Figure 1, and,

Figure 7 is a detail sectional view of one form of shock absorber which may be used with the apparatus.

Referring to the drawings the numeral 10 designates a pair of spaced supporting frames arranged at opposite sides of the apparatus. Each supporting frame includes a pair of vertical posts 11, and the lower ends of the posts at each side of the apparatus are connected by a horizontal 30 base member 12, which may be in the form of an angle iron, as shown in Figure 1. The posts 11 at opposite sides of the apparatus are connected by suitable cross braces 13, preferably in the form of tubular members welded to the posts 11.

The upper ends of the posts 11 at each side of the apparatus are connected by an upper horizontal supporting member 14, and each of these supporting members carries a bearing 15, as shown in Figures 1 and 2. A disk 16 is arranged 40 inwardly of each side frame member and these disks are provided with aligned trunnions 17 rotatably supported by the bearings 15. A tubular brace 18 may be welded at its ends to the disks 16 to assist in bracing the disks with respect to 50 each other. A hand wheel 19 is secured to each disk 16 by means of small braces 20, and it will be apparent that the disks 16, hand wheels 19 and trunnions 17 are preferably coaxial with each other.

A tumbler indicated as a whole by the numeral 21 is adapted to contain the clothes to be shaken out. This tumbler is arranged between the disks 16 and includes a preferably perforated cylinder portion 22 and a wall 23 at one end of the cylindrical portion. At the opposite end of the cylindrical portion 22, the casing includes a conical section 24 having a relatively large circular central opening 25. The tumbler is provided with 10 an axial stud 26 carried by the wall 23 and this stud may be rotatable in bearings 27 carried by a sleeve 28. The bearings 27 preferably act both as radial and thrust bearings to rotatably support the tumbler and prevent endwise movement 15 thereof. Outwardly of the sleeve 28, the wall 23 may be provided with reinforcing ribs 29, preferably welded thereto. The interior of the tumbler is provided with a plurality of lifting ribs 29', some of which are wider than the remaining ribs 20 and taper to decrease in width away from the opening 25.

The sleeve 28 is integral with a pair of radially extending arms 30 which are preferably tubular and are welded or otherwise rigidly secured to the 25 disks 16. The arms 30 and sleeve 28, being preferably integral with each other, form a relatively heavy brace between the disks 16 and constitute the sole supporting means for the tumbler. This 30 bracing means and the member 18 rigidly fix the disks 16 with respect to each other.

One of the disks 16 carries an electric motor 31 and this motor drives a belt 32 which passes around the cylindrical portion 22 of the tumbler. A suitable idler pulley 33 may be employed for 35 properly tensioning the belt 32. One of the trunnions 17 is preferably provided with an opening therethrough to receive a two-wire cable 34 leading to the motor. It will be apparent that the tumbler, disks 16, hand wheels 19 and motor 31 40 are bodily rotatable about the axis of the trunnions 17, and accordingly the motor retains a fixed relationship with the tumbler to drive the latter regardless of its position. It will be apparent 45 that the motor is so placed with respect to the elements with which it is bodily movable as to constitute a counterweight to assist in moving the elements between the two positions to be referred to. Additional counter-weights 35 (see Figure 4) may be employed if desired.

The tumbler, disks 16 and associated parts are 50 bodily movable to two positions, namely, the loading and operating position shown in solid lines in Figure 2 and the unloading position shown in broken lines. Means are provided for latching the tumbler in either of its two positions. Referring to Figures 2 and 5, the numeral 36 designates a relatively heavy leaf spring supported at one end as at 36' with respect to one of the legs 11. The free end of the leaf spring carries a 55 pair of spaced stop members 37 and 38 between which is arranged an upstanding pin 39, also carried by the leaf spring. A pair of stop fingers 40 and 41 is carried by the disk 16 adjacent the leaf spring 36, as shown in Figure 5. When the parts 60 are in the loading position shown in Figures 2 and 5, the stop finger 40 is arranged between the pin 39 and the stop member 38, and when the tumbler is in the unloading position, the stop finger 41 will be arranged between the pin 39 and the stop member 37. A pull rod 42 is pivotally 65 connected at its upper end as at 43 to the leaf spring 36 adjacent the free end thereof. The lower end of the pull rod 42 is connected to a 70 treadle 43 secured to a transverse rock shaft 44

having its ends rotatably supported by the base members 12. It will be apparent that depression of the treadle 43 pulls downwardly on the rod 42 to release the elements carried by the leaf spring 36.

Means for releasing the latch elements referred to is also provided for the forward end of the apparatus. Referring to Figures 3 and 6, the numeral 45 designates an arm carried by the shaft 44 and pivotally connected as at 46 to one end of the lever 47. This lever is pivotally supported intermediate its ends as at 48 and is provided at its other end with a pedal 49. It will be apparent that depression of this pedal has the same effect as the depression of the pedal 43, and the use of 15 the two pedals will be referred to later.

As previously stated, the tumbler is adapted to swing from the loading and operating position shown in Figure 3 and in solid lines in Figure 2, to the unloading position shown in broken lines 20 in Figure 2, and if desired, shock absorbing means may be provided for preventing too rapid movement of the tumbler as it approaches each of its two positions. In practice it has been found that such shock absorbing means assists in maintaining quietness in the operation of the apparatus. A rod 50 is pivotally connected at its upper end to one of the disks 16, as shown in Figure 3. This cylinder may communicate with the atmosphere 25 at its lower end and may be provided with a slot 30 53 extending throughout the greater portion of its length so that the piston 51 is freely movable except near the top of its stroke. A port 54 is provided in the upper end of the cylinder and it is controlled by a small inwardly opening check 35 valve 55. The cylinder may be pivotally connected as at 56 to a bracket 57 carried by one of the posts 11. It will be apparent that the cylinder 52 is adapted to swing about its pivot to adjust 40 itself to the position of the rod 50 as the latter moves incident to the movement of the tumbler.

Referring to Figures 1, 2 and 3, the numeral 58 designates a tray or table mounted forwardly of the apparatus and supported with respect thereto by angle irons 59 or similar elements secured to the forward legs 11 of the apparatus. The table 58 may be suitably braced as at 60. This table facilitates the loading of the apparatus by providing support for the baskets or other containers 50 for the clothes.

The operation of the apparatus is as follows:

The tumbler is shown in the loading position in Figure 3 and in solid lines in Figure 2. With the motor 31 operating the belt 32 will rotate the tumbler about the axis of the trunnion 26, and as previously stated, the motor is adapted to rotate the tumbler regardless of the position of the tumbler, since the motor maintains a fixed relationship with respect thereto. An operator may dump in the opening 25 a batch of damp clothes which have been passed through wringers or twisted to wring excess water therefrom. The tumbler is permitted to rotate through the necessary period of time, the clothes being repeatedly lifted and dropped by the ribs 29' during the rotation of the tumbler. Because of the tapered construction of the wider ribs 29', the articles have a tendency to move away from the opening 25, thus eliminating any tendency for the articles to fall out of the tumbler through the opening 70 25.

After the tumbling operation has been carried out to completion, the clothes will be well shaken out and loosened, and thus prepared for ironing. The operator in front of the apparatus may then 75

depress the pedal 49 preparatory to swinging movement of the tumbler to discharging position. When the tumbler is in the loading position referred to, the motor will occupy the position shown in Figure 4, and the substantial weight of the motor will lie to one side of the vertical plane of the axis of the trunnions 17, and the weight of such parts will overbalance the weight of the parts arranged at the opposite side of the plane referred to.

When the operator depresses the pedal 49, the inner end of the lever 47 will be raised and will transmit a corresponding movement to the inner end of the arm 45. The pivotal connection 48 includes a slot in one of the elements 45 or 47 to permit the movement of the parts referred to. Elevation of the arm 45 rocks the shaft 44, thus pulling downwardly on the rod 42 and the free end of the leaf spring 36. This action will release the finger 40 from the pin 39 and locking member 38, and the tumbler will be free to swing about the axis of the trunnions 17.

As previously stated, the weight of the motor 31, and any supplemental weight means associated therewith, such as the weight 35, overbalances the tumbler, and accordingly the tumbler is biased away from the loading position at all times when it is in such position. Thus it will be apparent that when the latch elements referred to are released by depressing the pedal 49, the tumbler will start to rotate in a clockwise direction as viewed in Figures 2 and 3. The overbalancing of the tumbler will not move it completely to discharging position but will provide an initial impetus overcoming the inertia of the parts, thus relieving the operator of the necessity of having to impart initial movement to the parts. With the apparatus constructed as shown, the tumbler will swing approximately 40 degrees from its loading position when the latching means is released. Prior to the point at which the tumbler would otherwise come to rest, the operator may grasp one of the hand wheels 19 and supply sufficient additional power to cause the tumbler to continue its movement to the unloading position shown in broken lines in Figure 2, and when the parts reach such position, the latch finger 41, rotating in a counter-clockwise direction, as viewed in Figure 5, will engage the locking member 37 to depress the free end of the leaf spring 36, whereupon the finger 41 will come into engagement with the pin 39 to limit further movement of the tumbler.

Under such conditions the tumbler will be in the broken line position shown in Figure 2 with the opening 25 facing downwardly. During the various operations referred to, the motor 31 will have continued the rotation of the tumbler, and as the tumbler is rotated in the discharging position, the articles will be discharged from the tumbler to a receiving table, as indicated in dotted lines in Figure 3 and designated by the numeral 61. The articles thus discharged will be in a loose, well shaken-out condition, ready to be fed to the ironers. As soon as the articles have been completely discharged from the tumbler, the operator may depress the pedal 43, which action releases the latching means from the locking finger 41, whereupon the tumbler is ready to swing back to the loading position to be reloaded with articles.

When the apparatus is in the unloading position, the motor 31 will be arranged to the left of the vertical plane of the trunnions 17, as viewed in Figure 2 and with the clothes discharged from

the tumbler the latter will be relatively light, and the apparatus will be even more overbalanced than when in loading position. Accordingly the tumbler has a substantial bias away from the unloading position, particularly after the articles have been discharged therefrom, and upon the releasing of the latching means, the tumbler will immediately start to swing away from the unloading position toward the loading position. With the apparatus constructed substantially as shown in the drawings, the impetus imparted to the tumbler from the loading position will cause the tumbler to increase its speed for about 75 degrees of rotation from the unloading position. Of course, it will be apparent that prior to the reaching of the loading position, the parts will be oppositely overbalanced, but the momentum of the parts after leaving the loading position will be sufficient to carry the tumbler completely to the loading position at which point it automatically locks, ready for the loading operation.

The pivotal connection of the shock absorber operating rod 50 may be placed in such a position that it swings to an equal extent on opposite sides of a plane passing through the trunnions 17 and the pivot 56 of the shock absorber. Accordingly the plunger 51 will occupy the same position adjacent the top of the cylinder 57 when the tumbler is in its loading and unloading positions. Throughout most of the stroke of the plunger 51, the upper end of the cylinder 52 is open to the atmosphere through the slot 53, and during such times, the plunger is freely movable. As it approaches the upper end of its stroke, however, the upper limit of the plunger will close the slot 53, thus trapping air in the upper end of the cylinder 52 and cushioning the approach of the tumbler to its two operative positions. The use of the shock absorber has been found to render the apparatus remarkably quiet in operation.

It will be noted that when the tumbler is in loading position its center from top to bottom and from end to end is below the axis of the trunnions 17, whereas its center is above such axis of rotation when in the unloading position. The parts may be arranged to make this difference in height even greater, and this feature constitutes an important point in the operation of the apparatus. It is desirable to discharge clothes to a receiving table of the character referred to, while at the same time it is desirable to eliminate the necessity of an operator having to lift a basket of wet articles to a substantial height. Accordingly it will be apparent that with the present apparatus the desired loading and unloading of the apparatus is greatly facilitated. Moreover, the apparatus involves the highly novel feature of being biased away from both of its positions referred to, thus rendering it unnecessary for the operator to use any substantial force in swinging the tumbler. As a matter of fact, it is not necessary for the operator to touch the apparatus when releasing it from the unloading position, since, upon the depression of the pedal 43, the tumbler will swing completely to its loading position and latch itself in such position.

It will be noted that the disks 16 and braces 18 and 30 combine to form a supporting yoke for the tumbler. The disks also serve to respectively support the driving motor and the latch fingers 40 and 41, and they add quite materially to the attractiveness of the apparatus.

It is to be understood that the form of the invention herewith shown and described is to be taken as a preferred example of the same and

that various changes in the shape, size and arrangement of parts may be resorted to without departing from the spirit of the invention or the scope of the subjoined claims.

5. I claim:
1. Apparatus of the character described comprising a tumbler supported for axial rotation, means supporting said tumbler for rotation about a substantially horizontal axis substantially perpendicular to the axis of said tumbler for bodily swinging movement through an arc of over 180° between loading and unloading positions, over-balancing means biasing said tumbler for swinging movement about said horizontal axis away from both of said positions, and means for holding said tumbler in either of said positions.
  2. Apparatus of the character described comprising a tumbler supported for axial rotation, means supporting said tumbler for rotation about a substantially horizontal axis substantially perpendicular to the axis of said tumbler for bodily swinging movement through an arc of over 180° between loading and unloading positions, over-balancing means biasing said tumbler for swinging movement about said horizontal axis away from both of said positions, means for holding said tumbler in either of said positions, said biasing means comprising a motor bodily movable with said tumbler, and means connecting said motor to said tumbler for axially rotating the latter.
  3. Apparatus of the character described comprising a tumbler supported for axial rotation and having an axial loading and unloading opening in one end thereof, means for supporting said tumbler for rotation about a substantially horizontal axis substantially perpendicular to the axis of said tumbler for bodily swinging movement between loading and unloading positions, the axis of said tumbler being substantially horizontal and arranged a substantial distance below said horizontal axis when said tumbler is in loading position, means biasing said tumbler for swinging movement about said horizontal axis away from either position, and means for holding said tumbler in either of said positions.
  4. Apparatus of the character described comprising a tumbler supported for axial rotation and having an axial loading and unloading opening in one end thereof, means for supporting said tumbler for rotation about a substantially horizontal axis substantially perpendicular to the axis of said tumbler for bodily swinging movement between loading and unloading positions, the axis of said tumbler being substantially horizontal and arranged a substantial distance below said horizontal axis when said tumbler is in loading position, means biasing said tumbler for swinging movement about said horizontal axis away from either position, means for holding said tumbler in either of said positions, said biasing means comprising a motor bodily movable with said tumbler, and means connecting said motor to said tumbler for axially rotating the latter.
  5. Apparatus of the character described comprising a tumbler, means for supporting said tumbler for rotation about its axis, a source of power for rotating said tumbler and bodily movable therewith, means for supporting said tumbler for rotation about a substantially horizontal axis substantially perpendicular to said first named axis for bodily swinging movement through an arc of over 180° between loading and dumping positions with the center of mass of the parts which rotate about said horizontal axis passing therebeneath, said horizontal axis being arranged between the positions of said center of mass in said positions of said tumbler, and means for limiting the swinging movement of said tumbler about said horizontal axis in said loading and dumping positions.
  6. Apparatus of the character described comprising a tumbler, means for supporting said tumbler for rotation about its axis, a source of power for rotating said tumbler and bodily movable therewith, means for supporting said tumbler for rotation about a substantially horizontal axis substantially perpendicular to said first named axis for bodily swinging movement through an arc of over 180° between loading and dumping positions with the center of mass of the parts which rotate about said horizontal axis passing therebeneath, said horizontal axis being arranged between the positions of said center of mass in said positions of said tumbler, means for limiting the swinging movement of said tumbler about said horizontal axis in said loading and dumping positions, and releaseable latch means for holding said tumbler in either of said positions.
  7. Apparatus of the character described comprising a tumbler, means for supporting said tumbler for rotation about its axis, a source of power for rotating said tumbler and bodily movable therewith, means for supporting said tumbler for rotation about a substantially horizontal axis substantially perpendicular to said first named axis for bodily swinging movement between loading and dumping positions with the center of mass of the parts which rotate about said horizontal axis passing therebeneath, the axis of said tumbler being substantially horizontal and arranged a substantial distance below said horizontal axis when said tumbler is in loading position, said horizontal axis being arranged between the positions of said center of mass in said positions of said tumbler, and means for limiting the swinging movement of said tumbler about said horizontal axis in said loading and dumping positions.
  8. Apparatus of the character described comprising a supporting frame, a tumbler supported in said frame for axial rotation, a motor for axially rotating said tumbler, said frame, tumbler and motor constituting a bodily movable unit, means for supporting said unit for bodily swinging movement about a horizontal axis substantially perpendicular to the axis of said tumbler through an arc of over 180° to move said tumbler between loading and unloading positions, the center of mass of said unit being arranged on opposite sides of the vertical plane of said horizontal axis in the two positions of said tumbler and movable in an arcuate path concentric with said horizontal axis and passing therebeneath when said tumbler moves between its two positions, and means for limiting the swinging movement of said tumbler about said horizontal axis in said loading and dumping positions.
